Design No. 3,261, dated November 17, 1868.

DESIGN FOR A TRADE-MARK

The Schedule referred to in these Letters Patent and making part of the same.

To all whom it may concern:

Be it known that I, D. FOERSTER, of Zanesville, in the county of Muskingum, and State of Ohio, have invented a new and original Design for a Trade-Mark for Crackers; and I do hereby declare that the following is a full, clear, and exact description thereof, which will enable others skilled in the art to make and use the same, reference being had to the accompanying drawings, forming part of this specification.

This invention relates to a new and original design for a trade-mark for cocoanut-crackers; and it consists in a representation of a branch of a cocoanut-tree, with leaves and two cocoanuts attached, the word "Cocoanut" being marked on the fruit, the name "Foerster's" over the top, and the word "Crackers" underneath, so that, with the design or illustration, the manufacturer's name and the article manufactured will be combined.

The accompanying drawing represents my design, A being a portion or branch of a cocoanut-tree, B, leaves thereof, and C C, two cocoanuts on the branch.

The word "Cocoanut" is painted, stencilled, or otherwise marked on the fruit or nuts, the word "Foerster's" above the branch, leaves, and fruit, and the word "Crackers" underneath them, as clearly shown in the drawing.

Having thus described my invention,

I claim as new, and desire to secure by Letters Patent—

A design for a trade-mark for "crackers," substantially as herein shown and described.

D. FOERSTER.
